ILLUMINABLE SIGN

Peter S. Rossi, Rte. 5, Joliet, Ill. 60451

Filed Oct. 22, 1968, Ser. No. 14,114

Term of patent 14 years

Int. Cl. D20—02

U.S. Cl. D96—12

FIG. 1.

FIG. 2.

FIG. 3.

I claim:

The ornamental design for an illuminable sign, substantially as shown.
